GOLF GAME APPARATUS

Hyman B. Lasting, Portsmouth, Va.

Application June 24, 1959, Serial No. 56,523

Term of patent 14 years

(Cl. D34—5)

In the drawings the dominant features of my design reside in the portions shown in full lines.

I claim:
 The ornamental design for a golf game apparatus, as shown and described.
